UNITED STATES PATENT OFFICE.

HARRY E. GALE, OF OGONTZ, AND WALTER D. BANES, OF PHILADELPHIA, PENNSYLVANIA.

FLAKING DEVICE.

1,410,008.

Specification of Letters Patent. Patented Mar. 21, 1922.

Application filed March 19, 1921. Serial No. 453,548.

To all whom it may concern:

Be it known that we, HARRY E. GALE and WALTER D. BANES, citizens of the United States, residents, respectively, of Ogontz, 5 Montgomery County, State of Pennsylvania, and Philadelphia, county of Philadelphia, State of Pennsylvania, have invented a new and useful Flaking Device, of which the following is a specification.

10 Our invention relates to improvements in flaking devices. The object is to provide simple, convenient and efficient means for severing portions of a substance from the main body thereof, in the form of extremely 15 thin flakes.

We accomplish this purpose by means of a sheet metal body having a substantially flat surface and provided in said surface with a series of slits, said slits arranged in 20 lines inclined to the longitudinal extension of the body and also so that the several lines of slits on one side of the medial line of said body converge toward corresponding lines of slits on the other side of said 25 medial line. These slits are so formed that one side wall or margin of each slit is raised above the opposite side wall of said slit and the raised side wall is preferably provided with an angular formation or somewhat 30 sharpened cutting edge.

Referring to the drawings, which illustrate merely by way of example suitable means for the embodiment of our invention:—

35 Fig. 1 is a plan view.

Fig. 2 is a side elevation.

Fig. 3 is a section on a greatly enlarged scale, on line 3—3 of Fig. 1.

40 Fig. 4 is a similar section on line 3—3 of Fig. 1.

Similar numerals refer to similar parts throughout the several views.

In the example shown in the drawings, the sheet metal body 5 is mounted on the 45 frame 6 having suitable supports 7 and 8, one at each end. One support, for example 7, is adapted to rest upon a table or other material receiving structure while the other support 8 serves as a handle to be grasped 50 by the operator.

As a preferable construction we have shown the support 7 provided with hook shaped formations for engaging the margins of a receptacle wall such as a sink 55 or tub.

The body portion 5 is provided with a series of slits 9 extending through the same. These slits 9 are very narrow, elongated openings having one long margin 10 raised above the opposite long margin 11 and 60 above the plane of the surface of the sheet metal body 5. These slits 9 are all arranged diagonally or inclined to the longitudinal extension of body 5.

Drawing an imaginary medial line longitudinally upon said body 5, it will be noted that the lines of slits on each side of said medial line converge toward each other as shown in Fig. 2, and that alternate lines of slits on either side of the medial line slightly 70 overlap each other and said medial line.

It will also be noted that these inclined slits 9 are staggered as to lines parallel with said medial line.

It will also be noted that when striking up 75 one longitudinal margin 10 above the other margin 11 of each slit, the elevated edge is sharpened or of angular formation as shown in Figs. 3 and 4 to facilitate in the operation to be described. This may be secured for 80 example by taking advantage of the thickness of the sheet metal and slightly turning one edge or corner further out than the other, as shown in Fig. 3, or the thickness of said margin may be reduced in any suitable way. 85

In operation the device is supported by the supporting part 7 resting, for example, upon a table or other supporting surface, while the part 8 is held in the hand of the operator. The substance to be flaked, such 90 as a cake of soap, is rubbed over the surface of body 5, so that when moved in direction of the arrow Fig. 2, the substance engages with the cutting raised margins 10 of the slits 9 and, due to the fact that the said 95 slits 9 are inclined to the lines of movement of the substance operated upon, and the cutting margins 10 correspondingly inclined, there is a shearing action of said cutting edges upon the substance, with the result 100 that very thin flat flakes or shavings are severed from said cake of soap, for example, which flakes are carried through said slits 9 and deposited beneath the same. The arrangement of the lines of slits, as above described, that is, with all the lines of slits on one side of an imaginary medial line, converging toward corresponding lines on the other side, serves to keep the object operated upon, as it is rubbed over the surface of 110

body 5, moving substantially along said medial line, so that the maximum efficiency is secured for all the severing edges or margins of the several slits.

5. What we claim is:—

1. In a device of the character described a sheet metal body provided with lines of separated slits inclined to the longitudinal extension of the body, each line comprising 10 a plurality of said slits formed each with one of its long margins raised above the opposite margin.

2. In a device of the character described a sheet metal body provided with lines of 15 short separated slits inclined to the longitudinal extension of the body, each line comprising a plurality of said slits formed each with one of its long margins raised above the opposite margin, said raised margin having a sharpened engaging edge.

3. In a device of the character described a sheet metal body provided with a series 20 of slits arranged in lines inclined to the longitudinal extension of the body and also so that the several lines of slits on one side 25 of the medial line of said body converge

toward corresponding lines of slits on the other side of said medial line, said slits formed each with one of its long margins raised above the opposite margin. 30

4. In a device of the character described a sheet metal body provided with a series of slits arranged in lines inclined to the longitudinal extension of the body, said slits also being staggered with respect to lines 35 parallel with said longitudinal extension, said slits formed each with one of its long margins raised above the opposite margin.

5. In a device of the character described a sheet metal body provided with a series 40 of slits arranged in lines inclined to the longitudinal extension of the body and also so that the several lines of slits on one side of the medial line of said body converge toward corresponding and slightly overlapping in 45 alternate order lines of slits on the other side of said medial line, said slits formed each with one of its long margins raised above the opposite margin.

HARRY E. GALE.
WALTER D. BANES.
